(57) **CLAIM**

The ornamental design for a tooth brush handle with brush head, as shown and described.

DESCRIPTION

FIG. 1 is a perspective view showing my design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.

(Continued)

The broken lines in the drawings illustrate features of the toothbrush that form no part of the claimed design.
